D. N. LAMBERT

GAS METER

Filed July 20, 1923.

By *David N. Lambert*
Attorney

UNITED STATES PATENT OFFICE.

DAVID N. LAMBERT, OF BROOKLYN, NEW YORK.

GAS METER.

Application filed July 20, 1923. Serial No. 652,798.

To all whom it may concern:

Be it known that I, DAVID N. LAMBERT, a citizen of the United States, residing at Brooklyn, in the county of Kings and State of New York, have invented new and useful Improvements in Gas Meters, of which the following is a specification.

My present invention relates to improvements in gas meters and more especially to those of the "dry" type employing expandable diaphragms for measuring the gas and registering mechanism actuated by such diaphragms for indicating the volume of gas which has passed through the meter.

The invention pertains more particularly to the means for operatively connecting the measuring diaphragms to the register actuating means. In meters of this type it is usual to employ an expandable diaphragm having a metal disk to which the meter actuating means is connected by a bracket composed of white metal or similar non-corrosive metal having a low melting point, the bracket having feet which are attached 25 to the diaphragm disk by solder and which must be detached from said disk by unsoldering them to enable the meter to be repaired. Such brackets, however, presented the objections that the soft metal feet there- 30 of are melted away, more or less, incident to the soldering or unsoldering thereof, so that the brackets frequently become unfit for use, owing to the deformation of the bases of the feet of the brackets in a manner 35 which precludes correct positioning of the bracket on the diaphragm disk.

The primary object of the present invention is to provide a novel and improved bracket which overcomes the difficulties and 40 objections which have been experienced with such brackets as heretofore constructed. The feet of the bracket, according to the present invention, embody inserts or sections of metal of high melting point and capable 45 of being soldered and unsoldered with respect to the diaphragm disk, with facility but without liability of melting away, although the body of the bracket may be composed of non-corrosive white metal of low 50 melting point, thus facilitating the operations of soldering and unsoldering the feet of the bracket relatively to the diaphragm disk and also insuring accurate fitting of the bracket against the diaphragm disk, so 55 that correct functioning of the register actuating mechanism is insured. The improved

bracket, according to the present invention, also embodies means for reinforcing it so that it will possess ample strength, and hence will not be liable to distortion or breakage, notwithstanding that the bracket may be composed largely of white metal or similar soft metal, the reinforcing means serving to securely anchor the inserts or sections of high melting point metal to the remainder of the bracket, thus forming a strong unitary structure. A further object of the invention is to provide a pivot shaft for operatively connecting the bracket to the register actuating means, which shaft will resist 60 corrosion which heretofore has interfered seriously with the correct functioning of meters of this type, the pivot shaft, according to the present invention, being composed preferably of Monel metal which is not only 65 non-corrosive, and hence free from binding in its bearings, but also possesses the requisite strength and wear resisting properties.

To these and other ends, the invention 70 consists in certain improvements and combinations and arrangements of parts, all as will be hereinafter more fully described, the features of novelty being pointed out particularly in the claims at the end of the 75 specification.

In the accompanying drawing:—

Figure 1 is a front elevation of a gas meter of the "dry" type, the front plate of the meter casing being removed to show a 80 bracket constructed in accordance with the present invention applied to the diaphragm disk thereof;

Figure 2 represents a section through a portion of the meter mechanism taken on 85 the line 2—2 of Figure 1;

Figure 3 represents, on an enlarged scale, a section taken through the bracket in the plane of the pivot shaft thereof; and

Figure 4 represents a transverse section 100 through the bracket on the line 4—4 of Figure 3.

Similar parts are designated by the same reference characters in the different figures.

The preferred embodiment of the invention is shown in the accompanying drawing and will be hereinafter described in detail. It is to be understood, however, that the invention is not restricted to the precise construction shown as equivalent constructions 105 are contemplated and such will be included within the scope of the claims.

2

In the present instance, 1 designates generally the casing of a gas meter of the "dry" type, meters of this class, as is well known to those skilled in the art, comprising an upper chamber 2 containing mechanism for actuating the gas registering means 3, and a lower compartment 4 which contains diaphragms 5, there being usually a pair of these diaphragms which are connected to 10 alternately receive a predetermined volume of gas from the inlet of the meter and in so doing expanding, the gas discharging alternately from the diaphragms to the outlet of the meter, the diaphragms contracting or 15 collapsing incident to the discharge of gas therefrom. The expansible diaphragms each comprise usually a metal disk 6 which is connected peripherally by a bellows 7 to the relatively fixed portion 8 of the diaphragm, this latter portion of the diaphragm being usually fixed to the stationary wall 9 contained within the meter casing, so that the diaphragm disk 6 will reciprocate incident to the expansion and contraction of the 20 diaphragm. Such reciprocating movements of the diaphragm disk are utilized, in meters of this type, to actuate the registering means, it being common to employ a rock shaft 10, the upper end of which is connected to suitable register operating means, and the lower portion of which has an arm or blade 11 fixed thereto, the free end of this arm or blade being operatively connected to the diaphragm disk 6, so that the reciprocating movements of the latter will impart 25 rocking movements to the shaft 10, the latter in turn acting to actuate the registering means.

The bracket provided by the present invention serves to operatively connect the arm or blade 11 to the diaphragm disk 6, it being usual and desirable to solder such bracket to the diaphragm disk, although unsoldering of the bracket becomes necessary 40 when the meter is to be repaired. The improved bracket, according to the present invention, comprises a main or body portion 12 which is composed preferably of white metal or other metal which is non-corrosive, 45 a soft metal of low melting point being usually preferred, owing to the facility with which it may be cast. This main or body portion of the bracket is formed with bearings 13 and 14 to receive a pivot shaft 15, 50 which latter is soldered or otherwise secured to the free end of the arm or blade 11 and serves to operatively connect the arm or blade 11 to the bracket. Difficulties have been experienced in meters of this type 55 using iron or steel pivot shafts, owing to the corrosion of the shaft and the consequent binding of the shaft in its bearings, but I have succeeded in eliminating such difficulties by constructing the pivot shaft 15 of 60 Monel metal which is non-corrosive and also

possesses the requisite strength and wear resisting properties. The feet of the bracket which are to be soldered to the face of the diaphragm disk 6, embody, according to the present invention, sections or inserts 15^a composed of a metal which has a melting point substantially above that of solder and which is capable of being readily tinned and soldered, brass being preferably used for these sections or inserts. These sections or inserts 15^a present edges which are adapted to fit truly against the face of the diaphragm disk 6 and are adapted to be soldered thereto, the relatively high melting point of the brass or other metal composing these sections or inserts enabling the bracket to be easily and quickly soldered or unsoldered without liability of melting away or deforming them, so that an accurate fit of the bracket to the diaphragm disk is always insured, and, moreover, no great degree of skill on the part of the workman is required in performing these operations.

In order to securely anchor the inserts to the main portion of the bracket, the edges of the inserts may be formed with recesses or notches 16 into which portions of the white metal composing the main portion of the bracket may flow and thus interlock the inserts with the main portion of the bracket. Also, to further anchor the inserts to the main portion of the bracket and to reinforce, stiffen and strengthen the bracket, a steel, iron or other strong metal rod 17 is preferably provided, the ends of this rod being secured firmly in holes 18 formed in the inserts 15^a, the rod bridging the inserts, and the portion 19 of the main white metal portion of the bracket preferably surrounds or envelops the rod, the composite structure thus formed providing a rigid union between the bearing and insert at one end of the bracket and the bearing and insert at the opposite end thereof. The construction herein shown may be advantageously manufactured by assembling the inserts on the ends of the reinforcing rod 17, placing such structure within a suitable mold and then casting the main portion of the bracket of white metal so that it will flow around the rod 17 and portions of the inserts, substantially as shown. The inserts are preferably tinned over their entire surfaces to avoid corrosion and to facilitate soldering of the inserts to the diaphragm disk.

The bracket provided by the present invention is capable of being soldered to and unsoldered from the diaphragm disk a great number of times without requiring replacement and accurate fitting of the bracket to the disk is always insured, and, moreover, no particular degree of skill or care is required of the workman. Furthermore, the composite bracket composed of different metals constitutes a unitary structure, possessing

great strength and rigidity and hence breakage of the bracket is not likely to occur and also the bracket is capable of withstanding distortion, so that accurate alinement of the 5 bearings of the bracket is maintained.

I claim as my invention:—

1. A bracket for attaching the register actuating means to the diaphragm disk of a gas meter comprising a main portion composed of a metal of low melting point and embodying bearings for a connecting shaft, and sections composed of metal of relatively higher melting point united with the main portion of the bracket and providing feet 10 adapted to be soldered to the diaphragm disk.

2. A bracket for attaching the register actuating means to the diaphragm disk of a gas meter comprising a part adapted for 20 connection with the register actuating means and composed of a metal of low melting point, and individual relatively spaced attaching feet composed of a metal of relatively higher melting point united with 25 the end portion of said part and adapted to be soldered to the diaphragm disk.

3. A bracket for attaching the register actuating means to the diaphragm disk of a gas meter comprising a portion composed

of a metal of low melting point forming 30 bearings for a connecting shaft, sections of metal of relatively higher melting point united with said bearings and forming feet adapted to be soldered to the diaphragm disk, and a reinforcement connecting said 35 sections.

4. A bracket for attaching the register actuating means to the diaphragm disk of a gas meter comprising a body portion having bearings for a connecting shaft, feet 40 embedded and anchored in the body portion and adapted for attachment to the body portion, and a reinforcement connecting together the feet and embedded in the body portion.

5. Means for operatively connecting the diaphragm disk to the register actuating means of a gas meter comprising a bracket attached to the diaphragm disk and having bearings of non-corrosive material and a 50 shaft composed of Monel metal fitted in said bearings and forming a pivotal connection between the bracket and the register actuating means.

In testimony whereof I have hereunto set 55 my hand.

DAVID N. LAMBERT.
